UNITED STATES PATENT OFFICE.

AUGUSTA R. ISAACS, OF PITTSBURG, PENNSYLVANIA.

FOLDING COT.

SPECIFICATION forming part of Letters Patent No. 619,485, dated February 14, 1899.

Application filed June 27, 1898. Serial No. 684,558. (No model.)

To all whom it may concern:

Be it known that I, AUGUSTA R. ISAACS, a citizen of the United States of America, residing at Pittsburg, in the county of Allegheny and State of Pennsylvania, have invented certain new and useful Improvements in Folding Cots, of which the following is a specification, reference being had therein to the accompanying drawings.

10 My invention relates to certain new and useful improvements in folding cots.

The object of my invention is to provide a cot of this character which when set up will be strong and durable and when folded will 15 form a compact package and occupy but little space. This I accomplish by the novel arrangement and combination of parts herein-after more fully described, illustrated in the accompanying drawings, and particularly 2c pointed out in the claim hereunto appended.

In the drawings, Figure 1 is a perspective view of my improved cot when set up without the removable cover or top. Fig. 2 is a cross-sectional view on the line $x-x$, Fig. 1. Fig. 25 2^a is a detail perspective view, partly broken away, of the side and end rails. Fig. 3 is an end view of a pair of the legs or supports when folded. Fig. 4 is a side view thereof. Fig. 5 is a perspective view of a part of my 30 removable top, showing the apertures formed therein to receive the securing-pins.

Like numerals of reference indicate corresponding parts throughout the several views of the drawings, in which—

35 1 indicates the side rails, and 2 the end rails, which have secured thereto on their upper edge a series of fastening-pins 3, which diverge outwardly therefrom. These fastening-pins are adapted to removably secure to

40 the rails the top 4 by the insertion of the pins into the apertures 5 formed in the top 4. The side and end rails are adapted to be secured together by means of the tenon 6, formed integral with the ends of the side rails and 45 which is adapted to be secured in the mortise

7 formed near the ends of the end rails. The end rails have formed therein mortises 8 and 8', which are adapted to receive the tenons 9 and 9' formed on the ends of the legs or supports 10 for securely holding the legs or 50 supports in position. These legs or supports are substantially V-shaped and are secured together at their center by means of the hinges 11 and are foldable, as shown in Fig. 3.

Secured to the legs or supports, as at 12, is 55 a screw-eye 13, which is adapted to receive the one end of the brace-rods 14, the other ends of these rods being screw-threaded and connected to a turnbuckle 15.

From the foregoing description, taken in 60 connection with the accompanying drawings, the operation of my improved folding cot can be readily understood.

Having thus described my invention, what I claim, and desire to secure by Letters Patent, is—

In a folding cot, the combination of a pair of side and a pair of end rails connected together by a mortise and tenon, said end rails being also provided with mortises 8 and 8', 70 a pair of supporting-legs, each of which is composed of two substantially V-shaped sections hinged together at their center and having a tenon formed on their upper end to engage the mortises 8 and 8', a pair of brace-rods connected at their one end to the supporting-legs and at their other end to a turnbuckle, a series of pins secured in the upper edge of the side and end rails, and a removable top or cover provided with apertures near its 75 edge to receive the pins and hold the top or cover in position, substantially as shown and described.

In testimony whereof I affix my signature in the presence of two witnesses.

AUGUSTA R. ISAACS.
